(57) **CLAIM**

The ornamental design for a construction toy box, as shown and described.

DESCRIPTION

FIG. 1 is a front, right, and top perspective view of a construction toy box showing my new design;

FIG. 2 is a front, left, and bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an environment perspective view thereof; and, FIG. 10 is a perspective view thereof, showing the construction toy box in an open state.

The broken lines shown in the drawings depict portions of the construction toy box that form no part of the claimed design.

The additional broken lines shown in FIG. 9 depict environmental subject matter that form no part of the claimed design.

1 Claim, 10 Drawing Sheets
